United States Patent Office

Des. 188,684

Patented Aug. 23, 1960

188,684

PITCHER

Marten Gottsegen, 2801 N. Sheridan Road, Chicago, Ill.

Filed Aug. 31, 1959, Ser. No. 57,382

Term of patent 14 years

(Cl. D44—21)

Fig. 1 is a side elevational view of a pitcher embodying my new design;

Fig. 2 is a reduced scale front elevational view thereof;

Fig. 3 is a reduced scale rear elevational view thereof; and

Fig. 4 is a reduced scale top plan view thereof.

I claim:

The ornamental design for a pitcher, substantially as shown.
